ELECTRIC RADIATION DEVICE

Kurt Wiegand, Berlin, Germany, assignor to
 General Electric Company, a corporation of
 New York

No Drawing. Application October 7, 1927, Serial
 No. 224,757. In Germany November 3, 1926

2 Claims. (Cl. 176—122)

The present invention relates to electric glow discharge devices, and in particular to devices for producing chemically active radiations, such as ultraviolet radiation.

5 It is the object of my invention to provide an improved source of such radiations, and especially a source of ultraviolet which is operable at a lower temperature than the devices heretofore used for such purposes, for example, quartz 60

10 mercury arc lamps.

These arc devices operate at such a high temperature that a relatively large air space is required between the arc device and the materials being treated. This fact entails an inefficient use 15

15 of the ultraviolet radiation. It has been proposed heretofore to use in place of mercury arc lamps a glow discharge device of the type commonly known as the "Moore tube" which is filled with a gas such as nitrogen or carbon dioxide at low 20

20 pressure. As devices of this type operate at lower temperatures the materials being treated can be brought directly into contact with the tube and the duration of treatment therefore can be materially reduced.

25 In accordance with the present invention the ultraviolet output of a "Moore tube" or similar type of glow device is increased, thereby rendering possible production of a given sterilizing effect in a shorter time. A device embodying this in- 30

30 vention comprises a glow device having an envelope consisting of material permeable to ultraviolet, such, for example, as silica or uviol glass, and containing a mixture of nitrogen and mer- 35

35 cury vapor. In the present form of the invention hydrogen is also present in addition to these gases.

In carrying out my invention an envelope of silica or uviol glass containing suitable electrodes and having ordinarily the usual tubular form is evacuated as usual and then is filled with nitrogen 40

40 at reduced pressure. A drop of mercury is also introduced into the device and preferably also some hydrogen. The nitrogen gas may have a pressure of 0.05 to 1 millimeter of mercury. The ultraviolet radiation field of nitrogen can be prac- 45

45 tically utilized up to only $280 \mu\mu$. The ultraviolet radiation of mercury, however, can be advantageously utilized up to $220 \mu\mu$. Furthermore, a better energy distribution is obtained by the addition of mercury vapor to the nitrogen and con- 50

50 sequently a more uniform distribution of the spectral lines. The proportion of the hydrogen to the nitrogen may be about 98 parts nitrogen and 2 parts hydrogen. In the Moore illuminating device with an ordinary glass bulb a special ef- 55

55 fort has been made to eliminate the hydrogen as

far as possible as its presence reduces the lighting efficiency of such lamps. In the present device, which is intended for a different purpose, the presence of hydrogen is an advantage.

The addition of the mercury vapor into glow 60 discharge devices does not produce any substantial increase in operating temperature of the device as the mercury vapor is used only as an auxiliary carrier of the discharge. For the op-

eration of a mercury vapor arc lamp of a given 65 length a current of about 3 amperes is required. For the present glow discharge device containing

nitrogen and mercury vapor a current of only about 50 to 80 milliamperes is required. This de- 70

crease in operating current entails also a de- 75

crease of operating temperature and therefore

permits such devices to be brought into direct

contact with a liquid to be treated with ultraviolet in such processes as sterilization, polymeriza- 75

tion, bleaching or vitamin enrichment.

What I claim as new and desire to secure by Letters Patent of the United States, is:—

1. An electric discharge ultra-violet generating device for ultra-violet treatment comprising an envelope permeable to ultra-violet radiation having solid electrodes sealed therein and containing a light radiant mixture comprising nitrogen, mercury vapor and hydrogen. 80

2. An electric discharge ultra-violet generating device comprising an envelope permeable to ultra-violet radiation having solid electrodes sealed therein and containing light radiant mixture of gases therein rich in ultra-violet radiation, said mixture comprising a discharge supporting gas in major proportion, a vaporizable material and another gas in minor proportion. 85
